Specification for Design.

Patented Feb. 27, 1917.

Application filed June 10, 1916. Serial No. 103,037. Term of patent 3½ years.

To all whom it may concern:

Be it known that we, JOSEPH J. SPRENGER and LUDVIG SORENSEN, citizens of the United States, residing at Indianapolis, in the county of Marion and State of Indiana, have invented a new, original, and ornamental Design for Hammer-Heads, of which the following is a specification, reference being had to the accompanying drawing, forming part thereof.

The figure is a perspective view, showing our new design.

Copies of this patent may be obtained for five cents each, by addressing the "Commissioner of Patents, Washington, D. C."

We claim as our invention:—

The ornamental design for a hammer head, as shown.

In witness whereof, we have hereunto set our hands at Indianapolis, Indiana, this seventh day of June, A. D. one thousand nine hundred and sixteen.

JOSEPH J. SPRENGER.
LUDVIG SORENSEN.
